JOHN JAY TONKIN, OF OSWEGO, NEW YORK.

THROTTLE-VALVE.

SPECIFICATION forming part of Letters Patent No. 357,511, dated February 8, 1887.

Application filed October 16, 1886. Serial No. 216,390. (No model.)

To all whom it may concern:

Be known that I, JOHN JAY TONKIN, of Oswego, in the county of Oswego, in the State of New York, have invented new and useful Improvements in Throttle-Valves for Steam-Engines, of which the following, taken in connection with the accompanying drawings, is a full, clear, and exact description.

This invention relates to the class of throttle-valves which are located inside of the steam-chest and mounted on the main valve; and the invention consists in an improved construction and combination of parts, whereby the throttle-valve is nearly or quite steam-balanced and the friction thereof is reduced to a minimum, all as hereinafter more fully described, and specifically set forth in the claims.

In the accompanying drawings, Figure 1 is a longitudinal vertical section of my invention as applied to a slide-valve of an engine; and Figs. 2 and 3 are transverse sections, respectively, on lines *x x* and *y y* in Fig. 1.

Similar letters of reference indicate corresponding parts.

25 A represents the top portion of a horizontal steam-cylinder provided with the usual valve-seat, B, steam-ports C C, and exhaust-port E; and H denotes the steam-chest provided with a port, F, through which it receives steam from the steam-pipe, which is connected to the steam-chest in the usual and well-known manner, and therefore not necessary to be here illustrated.

35 V represents the valve of the engine, which valve is of the class designated "slide-valves," and arranged to be reciprocated upon the valve-seat B in the usual manner.

When the steam-inlet port F is in the side of the steam-chest, as shown in Fig. 2 of the drawings, I provide the valve V with a longitudinal breast, I, bearing against a suitable smooth face, I', on the side of the interior of the steam-chest opposite the port F, and thereby enable the said valve to better resist the side pressure received from the steam entering through the said port.

The valve V, I make of a width to span the steam-chest, and of a length to make its ends extend beyond the steam-ports C C, and so the under side of the central portion thereof I

provide with the usual exhaust-cavity, a, communicating directly with the exhaust-port E of the cylinder.

55 b b represent live-steam passages formed inside of the valve V, and extending lengthwise of the central portion thereof above the exhaust-cavity a and down through the end portions of the valve, and having their ends in the face of the valve in proper positions in relation to the steam-ports C C of the cylinder, so as to bring them alternately in coincidence with the same during the movements of the valve, in the usual manner.

The top of the valve V, I provide with a supplemental valve-seat, c, which is extended 65 the entire length of said valve and is concave and of semicircular or segmental form in cross-section, and upon this valve-seat c, I mount the throttle-valve D, which is of cylindrical form and hollow, the cavity thereof 70 being concentric with the exterior. Said valve is to receive oscillatory motion from the usual spindle of a centrifugal steam-governor, which may be of any suitable and well-known form, and therefore requires no illustration in this 75 case.

The shaft or stem of the throttle-valve projects through a stuffing-box on the steam-chest, and the means for connecting said shaft or stem with the governor-spindle can readily be 80 devised by the skill of an engineer desiring to avail himself of my invention.

It will be observed that in the described construction and combination of the hollow cylindrical throttle-valve with the segmental 85 or trough-shaped supplemental valve-seat on the main valve only one-half or less than one-half of the surface of the throttle-valve is subjected to friction, and the valve is nearly or quite steam-balanced. 90

The ends of the throttle-valve D are closed, and the side of said valve facing the valve-seat c is provided with discharge-ports *ff*, coinciding with similar ports, *dd*, extending through the valve-seat and into the steam-passages *bb*. The upper part of the valve D is provided with a steam-inlet port, *e*, by which it receives steam from the interior of the steam-chest. The ports *dd* and *ff* are arranged in such relative position as to cause 100

them to coincide with each other, as shown in Fig. 2 of the drawings, when the governor is at rest, and thus the steam with which the steam-chest and throttle-valve D is charged has free entrance to the passages b b in the valve V, which passages are therefore charged with live steam simultaneously with the steam-chest. When the engine is set in motion, the live steam passes from the passages b b alternately into the steam-ports C C of the cylinder, and as the speed of the engine increases the governor turns the throttle-valve D on its axis and thereby cuts off in a greater or less degree the communication between the ports f f and ports d d.

The resultant reduction in the supply of steam to the cylinder A reduces the speed of the engine and causes the governor to turn the throttle-valve D back toward its original or normal position.

What I claim as my invention is—

1. In combination with the steam-chest of an engine, a slide-valve having both ends extending beyond the steam-ports of the cylinder and provided with an exhaust-passage at the center, and with internal steam-passages extending through the central portion of the valve over the exhaust-passage and through the

ends at the side facing the valve-seat, a concave supplemental valve-seat of semicircular form in cross-section on the aforesaid valve, ports in said supplemental valve-seat communicating with the internal steam-passages of the slide-valve, and an oscillatory tubular or hollow throttle-valve of cylindrical form riding on the segmental seat and having a steam-receiving port and steam-discharge ports, which latter are through the side facing the supplemental valve-seat, substantially as described and shown.

2. The combination of the steam-chest having the steam-inlet port F in one side and a smooth face, I', on the opposite side, and the valve spanning the steam-chest and provided with the breast I, bearing on the face I', substantially as and for the purpose set forth.

In testimony whereof I have hereunto signed my name and affixed my seal, in the presence of two attesting witnesses, at Oswego, in the county of Oswego, in the State of New York, this 12th day of October, 1886.

JOHN JAY TONKIN. [I. S.]
